LOUD-SPEAKER BAFFLE

Leonard Carduner, Roslyn Heights, N.Y., assignor to Wharfedale Audio Products, Inc., Port Washington, N.Y., a corporation of New York

Application November 4, 1957, Serial No. 48,343

Term of patent 3½ years

(Cl. D26—14)

FIG. 1

FIG. 2

FIG. 3

FIG. 4

Fig. 1 is a front perspective view of a loud-speaker baffle, showing my new design;
Fig. 2 is a top plan view;

Fig. 3 is a side elevational view; and
Fig. 4 is a rear elevational view thereof.

I claim:

The ornamental design for a loud-speaker baffle, as shown.
